United States Patent [19]
Izaki

[11] **Patent Number:** Des. 337,573
[45] **Date of Patent:** ** Jul. 20, 1993

[54] **ELECTRONIC COMPUTER**

[75] Inventor: Kenzo Izaki, Chiba, Japan

[73] Assignee: Kabushiki Kaisha Toshiba,
Kanagawa, Japan

[**] Term: 14 Years

[21] Appl. No.: 479,600

[22] Filed: Feb. 13, 1990

[30] **Foreign Application Priority Data**

Aug. 29, 1989 [JP] Japan 1-31156
